UNITED STATES PATENT OFFICE.

JOHN W. ANDERSON, OF CHICAGO, ILLINOIS, ASSIGNOR OF ONE-HALF TO CLARENCE POFFENBERGER, OF CHICAGO, ILLINOIS.

CONCEALED DOOR HINGE.

Application filed October 19, 1921, Serial No. 508,805. Renewed April 10, 1924.

To all whom it may concern:

Be it known that I, JOHN W. ANDERSON, a citizen of the United States, residing at Chicago, in the county of Cook and State of Illinois, have invented a certain new and useful Improvement in Concealed Door Hinges, of which the following is a full, clear, concise, and exact description, reference being had to the accompanying drawings, forming a part of this specification.

This invention relates to improvements in concealed door hinges.

As is well known, there is a pressing demand at present for a practical, substantial concealed hinge for doors, particularly in connection with automobile bodies of the closed type wherein the body and door curve inwardly at the bottom. The present practice requires the use of one or more outwardly projecting strap hinges in order to allow for the proper alinement of the pivotal axes of the vertical series of hinges secured to the door and body at different points along the curved formations thereof. Such outwardly projecting strap hinges are unpleasing in appearance and form projections on which the clothing may be torn.

Some attempts have been made to employ concealed hinges in automobile body construction but the same, so far as I am aware, present serious disadvantages for the reasons that they do not provide for sufficient clearance in the swinging movements of the door and also require cutting away so much of the door frame or stile as to seriously weaken the latter. As is well known in automobile construction, when the doors are closed, there is almost universally a bead or molding carried by the door which projects slightly over the crack left between the door and body when the door is in closed position, and provision must be made for throwing or swinging the door with sufficient clearance that said projecting strip of molding or bead will not engage with the corresponding molding on the framework, in order to avoid marring or indentation. Furthermore, the types of concealed hinges heretofore proposed for use on automobiles having an inward bottom curvature on the body and door do not allow sufficient clearance to permit the hinges being properly vertically alined in the relatively narrow wood to which the hinges must be applied.

One object of my invention is to provide a

concealed type of hinge for doors, and more particularly for use on automobiles, which requires the minimum depth and width of mortise or recess in the woodwork for a predetermined clearance between the door and framework when the door is swung open.

Another object of my invention is to provide a concealed door hinge of the type indicated in the preceding paragraph such that, for a given size of mortise or recess required to be cut from the woodwork, a greater clearance or throw will be allowed the door in its opening movements than in any previous type of concealed hinge.

Another object of the invention is to provide a concealed door hinge wherein are combined minimum size and greater throw than concealed hinges of prior constructions to thereby adapt a plurality of my improved hinges to be properly alined with greater latitude in the woodwork of limited width wherein the door and door frame are curved in the direction of their length, as in automobile body construction.

Other objects of my invention are to provide a hinge of the character indicated in the preceding paragraphs which may be manufactured at comparatively small expense with the principal parts thereof in the form of die pressings, which may be assembled and applied with a minimum of labor, and which is strong, durable and efficient in service.

In the drawing forming a part of this specification, Figures 1 and 2 are horizontal, sectional views corresponding to the section lines 1—1 and 2—2 respectively, of Figure 3, illustrating one embodiment of my improved hinge as applied to automobile body construction. In Figure 1, the relation of the parts is shown in dotted lines when the door is opened. Figure 3 is a vertical sectional view in the plane of the usual crack left between the adjacent edges of the door and door frame when the door is in closed position. Figure 4 is a horizontal sectional view similar to Figure 2 but illustrating the door in open position and with the journal bearing locking block loosened to illustrate the manner of assembling and disassembling the parts. And Figure 5 is a detail perspective of one of the main parts of the hinge.

In the drawing, 10 indicates the framework surrounding a door opening of an

automobile body of the closed type and 11 a portion of the corresponding door. As customary in automobile construction, the door frame or body portion of the car is 5 provided with a molding strip 10^a and the door with a corresponding molding strip 11^a, the latter projecting over the usual crack or gap between the adjacent edges of the door and door frame when the door is closed so 10 as to conceal the crack or joint, said projecting edge of the molding being indicated at 11^b. For convenience of description and claims, the side to which the door swings 15 will be referred to as the outer side with respect to the woodwork of the door frame, door and other parts.

In carrying out my invention, I employ what may be termed a housing A; a plate B; a block C; a retaining screw or bolt D; and 20 a nut block E.

In the arrangement shown, the housing A is recessed or mortised into the frame 10 and the plate B is secured to the door. Said 25 housing A is preferably in the form of a die pressed sheet metal product of suitable gauge since the form thereof readily lends itself to a die pressing operation. Said housing as shown, is formed on the face thereof adjacent the door edge with top and bottom flanges 12-12 suitably apertured and counter-bored to accommodate upper and lower sets of flush wood screws 13-13. Inwardly of the plane of the flanges 12-12, the housing A is formed on its outer side 30 with an integral wall 14 of a depth corresponding to the maximum depth of the mortise required, said side wall 14 merging with two bottom walls 15-15 extending at right angles to the side wall 14 and also with an 35 inclined partition 16. Said bottom walls 15-15 are continued integrally with inner side walls 17-17 parallel to the outer side wall 14, as best indicated in Figure 1. The 40 inclined or diagonal partition 16 is extended from the bottom outside corner of the housing to the exposed face of the housing but at the inside corner thereof as indicated at 45 16^a in Figure 2. Said inclined partition 16 is in a plane intermediate the portions of the 50 housing defined by the walls 15 and 17 and the integral structure is maintained by triangular horizontally extending webs 18-18, leaving in the back of the housing a triangular 55 recess to accommodate the nut block E and the end of the screw bolt D, as shown in Figure 2. It will also be understood that upper and lower walls are provided as indicated at 19-19 in Figure 3 extending horizontally from the bottom of the housing to 60 the flanges 12-12. It will be noted also that the inclined partition 16 provides on the interior of the housing a triangular space to accommodate the block E as best 65 shown in Figure 2.

Referring particularly to Figures 2 and 4,

it will be noted that, where the inclined wall 16 merges with the outer side wall 14 at the bottom of the housing, as indicated at 20, the interior surface is made rounded so as to provide a partial journal bearing. This feature of the construction is of importance inasmuch as it allows me to locate the bearing or axis of the swinging part of the hinge at a point which is the nearest possible to the molding 10^a and at the nearest possible 75 point to the bottom of the housing of any given or predetermined depth, this feature in turn allowing for greater clearance as hereinafter described.

The hinge plate B consists of a rectangular plate section proper as indicated at 21 and a pair of integral arms 22-22, as best shown in Figure 5. The plate section 21 is made of suitable width, thickness and height and is provided at the top and bottom thereof with suitable counterbored apertures 23-23 to accommodate wood screws for securing the plate to the door 11. The plate section 21 is preferably applied flush with the edge of the door as shown clearly in 90 Figures 1 and 2.

The arms 22-22 are integral with the plate section 21 and extend for a portion of their length at right angles to the plate section 21 as indicated at 22^a. Said arms 22 are then bent so as to extend horizontally and parallel with the plate section 21 as indicated at 22^b. The arms thus formed are vertically separated for a distance slightly greater than the width of the inclined partition 16 so that said arms 22 are adapted to straddle said inclined partition in moving into the housing. The free ends of the extensions 22^b are integrally united by a vertically extending journal or pintle section 24 arranged parallel to the plate section 21 and in a plane flush with the outer edge of said plate section 21, as shown in Figure 2. Said journal section 24 is adapted to be positioned in the partial journal bearing 20 and, as will be obvious, the arms 22^a-22^b are freely movable into and out of the upper and lower triangular pockets of the housing heretofore described. When the door 11 is in closed position, the sections 22^b of said arms will lie flat against the bottom walls 15 and the sections 22^a will lie flat against the inside walls 17-17, as best shown in Figure 1. When the door is in fully open position, the sections 22^b of said arms will lie flat against the outer wall 14 of the housing as shown in Figures 1 and 2 and in this connection, it will be noted that a very substantial and rugged limiting stop is thus provided to determine the limit of opening movement of the door. With the arrangement of the arms 22-22, above described, it will be seen that I obtain the maximum possible length for both the sections 22^a and the sections 22^b which may be accommodated within the 130

housing and thus, in turn, obtain the maximum possible clearance between the door and the frame and between the molding 11^a and the molding 10^a during the swinging movements of the door. As clearly indicated in Figure 1 by the dotted outlines of the door in open position, there is more than a half inch clearance between the projecting edge 11^b of the molding and the outer face of the molding 10^a. From this it will be evident that wide latitude is allowed in placing the hinges on the door and framework having curvature while at the same time maintaining the pivotal axes of the hinges in vertical alinement and leaving sufficient clearance throughout the entire length of the door between the moldings to prevent injury to any of the parts. In this connection, reference may be had to the disclosure in Figure 7 of my co-pending application 464,195, filed April 25, 1921. In the drawing of the present application, the parts are shown full size to substantially accurate scale.

The two main parts of the hinge are held in assembled relation by the blocks C and E and the screw D. The block C is of triangular form having an inclined face 116 corresponding to the partition 16 and an outer face 25 parallel to the outer side wall 14 of the housing. At the corner where the faces 25 and 116 merge, a partial journal bearing 26 is formed, arranged to fit over the journal section 24 and, in conjunction with the partial bearing 20, complete the entire journal bearing for the journal section 24. The block C is of a thickness corresponding to the vertical dimension of the partition 16 and consequently may be seated between the arms 22-22. When in operative position, the face 27 of the block C lies flush with the surface of the flanges 12 of the housing A.

The block C is provided with an elongated slot 28 therein through which extends the shank of the screw bolt D. Said slot 28, at one end in the face 27, is enlarged as indicated at 28^a to accommodate the head of the screw bolt D when the parts are in operative position so as to have the end of the screw bolt flush with the face 27. By means of the slot 28, as best indicated in Figures 2 and 4, it will be seen that the block C can be slipped outwardly along the partition 16 when the screw bolt is loosened so as to leave sufficient clearance for inserting and withdrawing the journal section 24. This facilitates the assembling of the parts of the hinge after the housing has been secured to the framework and the plate B to the door and also allows the dismounting of the door at any time desired without detaching the housing or plate B from its respective support.

The nut block E is also of triangular form and fits against the bottom side of the

partition 16 and is located between the upper and lower triangular pockets of the housing and restricted against turning by the walls 18-18. The block E is threaded so as to act as a nut in operation with the screw bolt D in holding the parts in assembled relation. Preferably the block E is formed with an integral lug 29 adapted to fit into a corresponding depression 30 stamped into the partition 16 so as to prevent the block E from sliding lengthwise of the partition 16.

The housing A, as heretofore described, and the plate B are preferably formed as die pressings so as to reduce the cost of manufacture to a minimum and insure accuracy as to dimensions. The blocks C and E are preferably in the form of castings suitably machined.

As heretofore indicated, the hinge shown in the drawing is to substantially an accurate full size scale from which it will be seen that the over-all depth of the housing A is approximately 1 $\frac{5}{8}$ ", the width 1 $\frac{9}{16}$ ", and the total height of the housing proper, without considering the flanges 12-12, is 1 $\frac{13}{16}$ ". As shown in Figure 1, the clearance exceeds a half inch. On account of the small size of the mortise or recess required for the housing, the framework is not materially weakened and I believe I am the first to provide, in a concealed type of hinge as compact as above indicated, a clearance in any wise approximating a half inch.

I have herein shown and described what I now consider the preferred manner of carrying out the invention but the same is by way of illustration only and not by way of limitation. All changes and modifications are contemplated which come within the scope of the claims appended hereto.

I claim:

1. In a concealed hinge for doors and the like, the combination with a housing adapted to be recessed into one of the members to be hinged, said housing being provided with a partial journal bearing at its bottom corner on the outer side; of a plate adapted to be secured to the other of the members to be hinged, said plate having an arm rigid therewith and extending therefrom, first substantially at right angles and then substantially parallel to the plate proper, the outer end of said parallel portion of said arm being provided with a journal section arranged parallel to and extending lengthwise of the plate and adapted to be seated within said partial journal bearing of the housing; and detachable means, secured within the housing, having a cooperable partial journal bearing fitting over said journal section to retain the same in place.

2. In a concealed hinge for doors and the like, the combination with a housing adapted to be recessed into one of the members to

- be hinged, said housing having an outer side wall and a bottom wall and provided with an integral partial journal bearing at the corner between said walls; of a plate 5 adapted to be secured to the other of the members to be hinged, said plate having an arm rigid therewith and extending therefrom first substantially at right angles and then substantially parallel to the plate and 10 at the end thereof provided with a journal section adapted to be seated in said integral partial journal bearing of the housing; and detachable means cooperable with said journal section for retaining the latter in position. 15
3. In a concealed hinge for doors and the like, the combination with a housing adapted to be recessed into one of the members to be hinged, said housing being provided with a partial journal bearing at its bottom corner on the outer side thereof; of a plate adapted to be secured to the other of the members to be hinged, said plate having a pair of spaced arms rigid therewith and extending 20 therefrom first substantially at right angles and then substantially parallel to the plate proper, the outer face of said arms being connected by a journal section arranged lengthwise of the plate and adapted to be seated in said partial journal bearing; and detachable means secured within the housing having a cooperable partial journal bearing 25 to retain said journal section in position. 30
4. In a concealed hinge for doors and the like, the combination with a housing adapted to be recessed into one of the members to be hinged, said housing having an outer side wall and a bottom wall and formed with an integral partial journal bearing at the corner between said walls; of a plate adapted to be secured to the other of the members to be hinged, said plate having a pair of spaced arms rigid therewith and extending 35 therefrom first substantially at right angles and then substantially parallel to the plate proper, the outer ends of said arms being connected by a journal section arranged parallel to the plate proper and adapted to be seated on said partial journal bearing; and means cooperable with said journal section for retaining the latter in operative position. 40
5. In a hinge of the character described, the combination with a housing adapted to be mounted on one of the members to be hinged, said housing having an outer side wall and a bottom wall rounded at their 45 juncture to provide an interior partial journal bearing at the nearest possible point to the outer side and bottom of the housing; of a cooperable hinge plate adapted to be secured to the other of the members to be 50 cooperable with said partial journal bearing, the arm being accommodated within the housing when the door is in closed position; and means for holding said journal section in operative position. 55
6. In a hinge of the character described, the combination with a housing adapted to be mounted on one of the members to be hinged, said housing having an outer side wall and a bottom wall rounded at their 60 juncture to provide an interior partial journal bearing at the nearest possible point to the outer side and bottom of the housing; of a cooperable hinge plate adapted to be secured to the other of the members to be 65 cooperable with said partial journal bearing, the arm being accommodated within the housing when the door is in closed position; and means for holding said journal section in operative position, said arm being formed integrally with the plate and having a sub- 70 stantially right-angular bend therein. 75
7. In a hinge of the character described, the combination with a housing adapted to be recessed into one of the members to be hinged, said housing being formed with a right-angular pocket in the bottom thereof and with a partition inclined from the bottom outer side toward the face of the housing, of a cooperable hinge plate adapted to be secured to the other of the members to be hinged, said plate having an arm rigid therewith, said arm having a right-angular bend therein adapted to be accommodated in said right-angular pocket; means providing a pivotal connection between the free 80 end of said arm and the housing, said means including a detachable block secured to said 85 inclined partition of the housing. 90
8. In a hinge of the character described, the combination with a housing adapted to be mortised into one of the members to be hinged, said housing being provided with a centrally disposed inclined partition and right-angular pockets on each side of said 95 partition; of a cooperable hinge plate, said plate having a pair of spaced arms extending therefrom, said arms having right angular bends therein adapted to be accommodated in the respective right-angular pockets, the free ends of said arms being 100 connected by a journal section; and means for retaining said journal section in operative position including, a block detachably secured to said inclined partition. 105
9. In a hinge of the character described, the combination with a housing adapted to be mortised into one of the members to be hinged, said housing being provided with a centrally disposed inclined partition and right-angular pockets on each side of said 110 partition; of a cooperable hinge plate, said 115
- 60 65 70 75 80 85 90 95 100 105 110 115 120 125 130

plate having a pair of spaced arms extending therefrom, said arms having right-angular bends therein adapted to be accommodated in the respective right-angular pockets, the 5 free ends of said arms being connected by a journal section; and means for retaining said journal section in operative position including, a block mounted on said inclined partition, said block having a slot therein, 10 and a screw extended through said slot and said partition.

10. In a hinge of the character described, the combination with a die pressed sheet metal housing having arm-receiving pockets 15 therein and an integrally formed partial journal bearing; of a co-operable die pressed hinge plate having a plate section proper and integral spaced arms extending therefrom, the free ends of said arms having an 20 integral journal section formed therebetween and adapted to be seated on said partial journal bearing; and detachable means for securing said journal section in operative position.

25. 11. In a concealed hinge for doors, the combination with an element to be secured to one of the members to be hinged, said element being provided with a portion extending into said member, said portion being 30 provided with a partial journal bearing; of a plate adapted to be secured to the other of the members to be hinged, said plate having an arm rigid therewith and extending therefrom, first laterally and then substantially 35 parallel to the plate proper, the outer end of said parallel portion of said arm being provided with a journal section arranged parallel to and extending lengthwise of the plate, and adapted to be seated on said 40 partial journal bearing of the extended portion of said element; and means detachably secured to said element having a co-operable

journal bearing section adapted to retain said journal section in place.

12. In a concealed hinge for doors, the 45 combination with an element adapted to be secured to one of the members to be hinged, said element being provided with a portion extending into said member and parallel to that side thereof to which the door opens; 50 of a plate adapted to be secured to the other of the members to be hinged, said plate having an arm rigid therewith and extending therefrom, first laterally and then substantially 55 parallel to said plate and extending lengthwise of said portion of said element when the door is open; and means including a journal element and a sectional journal bearing embracing said element for pivotally connecting said element and the free end of said arm on an axis parallel to the plate and at the inner end of said element.

13. In a concealed hinge for doors and the like, the combination with a housing adapted to be recessed into one of the members to be hinged, said housing being provided with a journaled bearing element; of a plate adapted to be secured to the other of the members to be hinged, said plate having an arm rigid therewith and extending 70 therefrom, first substantially at right angles and then substantially parallel to the plate proper, the outer end of said parallel portion of the arm being provided with a journal section arranged parallel to and extending 75 lengthwise of the plate and adapted to be seated on said journal bearing element of the housing; and detachable means secured within the housing engaging over the journal section to retain the same in place. 80

In witness that I claim the foregoing I have hereunto subscribed my name this 29th day of Sept. 1921.

JOHN W. ANDERSON.
